CLAIM

The ornamental design for a pair of shoes, as shown and described.

DESCRIPTION

FIG. 1 is a front, left, and top perspective view of a pair of shoes, showing my new design for a left foot;

FIG. 2 is a front, left and bottom perspective view of a pair of shoes, showing my new design thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a rear elevation view thereof.

A pair of shoes for a right foot is a mirror image of the pair of shoes for a left foot as shown in FIGS. 1 to 8.
